PORTABLE DESK

David Barron O'Kelly, Bishopville, S. C.

Application December 31, 1936, Serial No. 118,496

10 Claims. (Cl. 40—52)

My improvements relate to portable desks for use by public speakers, readers, lecturers, actors, etc., and the objects of my invention are, first, to provide a portable desk in which an address or speech may be placed in the form of a scroll adapted to be unrolled and moved to progressively reveal the address or speech to the speaker's or user's view during the delivery of the address or speech; second, to provide a speaker's desk with a power driven mechanism for feeding a scroll containing the speaker's words thereon past the vision of the speaker; third, to provide a speaker's desk adapted for portable use and automatically and mechanically operated; fourth, to provide a portable desk for speakers or musicians or similar uses and adapted to be operated either by power driven means or by manually operated means; fifth, to provide a speaker's desk equipped with an automatically operated scroll together with an automatically operated clock mechanism for regulating the address of the speaker or user to a predetermined time; sixth, to provide a speaker's desk having automatically operated scroll means with means for causing the scroll means to pause for a predetermined length of time while being read by the speaker; seventh, to provide a speaker's desk having a scroll with power driving means equipped with a Geneva wheel mechanism to provide intermittent operation of the scroll; eighth, to provide a speaker's desk having a roller supported scroll with power driving means equipped with a free wheeling mechanism to enable rolls and the scroll to be manually operated as desired; ninth, to provide a speaker's desk having a power driven scroll with means for changing the speed of the scroll; tenth, to provide a speaker's desk having a scroll with a driving means utilizing friction or gear drive mechanism; eleventh, to provide a speaker's desk with an adjustably mounted lens member for magnifying a scroll from which the words of the speaker or user are being read; twelfth, to provide a speaker's desk having a power driven scroll and a clock mechanism with a switch mechanism for controlling the operation of the clock mechanism and power driven scroll; thirteenth, to provide a speaker's desk having a power driven scroll means mounted on a base member with a cover housing pivotally mounted on the base member and adapted to enclose and protect the power driven scroll means; fourteenth, to provide a speaker's desk with a lens magnifying member positioned to best accommodate the correct optical vision of the speaker; and fifteenth, to provide a speaker's desk adapted for use by a musician

or similar performer in the playing of music indicated on a movably mounted scroll or similar member.

I attain these objects by the mechanism illustrated in the accompanying drawings, in which:—

Figure 1 is a plan view of my portable desk and disclosing a portion of it broken away to more fully disclose the scroll and rolls; Fig. 2, a side view of the portable desk with its cover housing broken away substantially on the line 2—2, Fig. 1, to more clearly disclose the mechanism therein; Fig. 3, a partial sectional view of the portable desk taken on the line 3—3, Fig. 2; Fig. 4, a partial sectional view of the portable desk taken on the line 4—4, Fig. 3; Fig. 5, a partial sectional view of the portable desk taken on the line 5—5, Fig. 3; Fig. 6, a front view of the portable desk drawn to a smaller scale than that of Figs. 1 and 2; and Fig. 7, a partial sectional view of the portable desk taken on the line 7—7, Fig. 3.

Similar numerals refer to similar parts throughout the several views.

My invention incorporates improvements on the portable desk disclosed in my U. S. Patent 1,636,783, issued July 26, 1927, and the mechanism disclosed in said U. S. patent has been improved by the application of automatic and manual control together with power driven mechanism to provide a portable automatic speaker's desk.

My portable desk in this present application is designed to meet the needs of the every day user of reading matters such as radio announcers, casting directors, actors, readers and lecturers such as preachers, teachers, judges, lawyers, doctors, business executives, and in fact anyone utilizing the compilations of definite data which are to be used accurately and dispensed with speed and precision in a public address or stated matters.

My portable desk provides a mechanism which is a necessary adjunct in practically all walks of commercial life and in which there are many uses therefor.

It is also adapted to be utilized advantageously in the music world to hold and dispense the music as the musician desires.

My portable desk comprises the base or floor member 1 having an upper land or portion 2 for supporting the driving, control and scroll support mechanism of my invention, said driving, control and scroll support mechanism being enclosed by the covering or housing 3 which is secured to the land 2 of the base member 1 by a hinge mechanism 4 provided with the flanges 5

secured to the cover 3 by the rivets 6, the hinge mechanism 4 being further provided with the flanges 7 secured to the land 2 by the screws 8.

The cover 3 is preferably constructed of material which will provide light weight and economy in manufacture and the lower edge portion of the cover 3 may be folded as at 9 to provide a bead therearound and to reinforce the open side of the cover 3 as well as to provide for proper 10 stiffening characteristics of the portion which contacts the land 2.

The cover 3 is provided with the handle 10 which forms a portion of the lock mechanism 11 which is of conventional key operation and 15 construction and is adapted to lock the cover housing 3 and the base member 2 together.

The cover 3 is provided with a suitable opening through which extends the clock mechanism 12 which is secured to the cover 3 by a plurality 20 of screws 13. The clock mechanism 12 is an electrical timing clock which enables the user or speaker to regulate his talk or reading to a given time in accordance with the given number of minutes as the case may be even to split 25 seconds.

The clock mechanism 12 is provided with a land or face portion 14 through which the time recordings of the clock mechanism 12 are visible to the speaker at all times.

30. The cover 3 is also provided with the opening 15 through which extends the lens 16 which is a magnifying lens and which is provided with the correct curvature to enable the user to satisfactorily observe the reading matter on the scrolls, paper or sheet 17 which is tightly 35 stretched and extends under the lens 16 which fits approximately at an angle of 45° to accommodate the correct optical vision of the speaker when the portable desk is suitably supported on a table, stand or similar member in front of the speaker. Also the clock mechanism is inclined to more readily accommodate its observance by the vision of the speaker.

40. The lens 16 is supported by having its end 45 portions entered within the hollow extension portions 18 which face inwardly and are suitably secured on the plates or bracket members 19 which are secured to the side walls of the cover 3 by means of screws or bolts 20 which are provided 50 with a handle or knob portion 21, the screws 20 extending through the slots 22 in each of the plates or brackets 19 to be secured by nut members 163 in a conventional manner.

55. Thus the plates or brackets 19 are adjustably mounted to permit adjusting the magnifying lens 16 to various positions to permit the reading matter on the scroll 17 to be best observed by the speaker.

60. The scroll, sheet or paper 17 is adapted to be printed with the message or speech to be delivered by the speaker or user, and is then wound on the roller or cylindrical member 23 with one end of the scroll, sheet or paper extending over the upper roller 24, and then extending as indicated by the portion 25 to the master roller 26 to which it is suitably secured to permit its being rolled thereon, each of the rollers 23 and 26 being provided with the tubular portions 27 which are closed at their ends by the bushings 28 which are provided at each end with a flange 29 to retain the rolled sheets on the rollers.

70. It is to be noted that the rollers 23 and 26 are provided with the bushing members 28 which have a larger flange 29 than the bushing members of the roller 24, as the roller 24 engages

the scroll in an idler capacity only, whereas substantially the total scroll is rolled or wound initially upon the roller 23 and is then fed or actuated from off of the roller 23 on to the master roller 26, the flange 29 thus being necessarily 5 larger to extend for the full thickness of the total scroll on the rollers 23 and 26, whereas only a single sheet or thickness of the scroll engages and passes by the roller 24.

One of the flanges 29 of the roller 23 is provided with an extension portion 31 which has a bearing in the bushing 32 which is secured to the flange 33 of the bracket 34 as by riveting as indicated at 35, Fig. 5.

The bracket 34 is further provided with a 15 flange 36 through which extends the shaft 37 which extends into the bore 38 of the extension portion 31, the shaft 37 being provided with a slot 39 which engages the extension portion 40 of the stud 41 which fits within the bore 38 of 20 the extension portion 31, said bore having a size sufficient to receive therein the shaft 37, the stud 41 being provided with an extension portion 42 which is secured by being pressed into a bore of one of the flanges 29 as disclosed in Fig. 5. 25

The resilient member or spring 43 surrounds the shaft 37 and extends between an inside surface of the bushing 31 and the collar 37A to exert a pressure on the extended portion of 31 so that the roller 23 is always urged toward a tight 30 engagement with the bushing 44 which is secured to the flange 45 of the bracket 46 by riveting as indicated at 47.

A stud 48 has a bearing in the bore of the bushing 44. The bracket 46 is secured to the base 35 member 1 by screws 49 and the bracket 34 is secured to the base member 1 by the screws 50. The handle or knob 51 is mounted on the shaft 37 and is secured thereto by the pin 52.

The bushing 53 is fixedly secured to the flange 40 36 by riveting as at 53A, or by similar means, and forms a bearing for the shaft 37, the shaft 37 normally being held out of engagement with the extension portion 40 by the spring 43, the shaft 37 being adapted to be slidably moved to 45 engage the extension portion 40 when it is desired to rotate the roller 23 manually by the handle or knob 51.

Thus my portable desk may be operated manually when the driving means, such as the electric motor assembly A, is inoperative, or if the operator desires to advance, retard or retract the reading matter, thus permitting the scroll and rollers to be moved forward or backward at the will of the operator at any time irrespective of 55 the operation of the motor or driving mechanism hereinafter described.

In a similar way the roller 26 is rotatably supported on a bracket 34 located, however, at the opposite side of the portable desk assembly due 60 to the positioning of the driving mechanism for the roller assembly adjacent the other end of the roller 26 at the same side of the portable desk assembly to which the knob or handle 51 is located by the roller 23. 65

The roller 26 is supported at its end opposite to one of the brackets 34 by the stud 55 which is provided with an extension portion 56 which enters a bore of one of the flanges 29 of one of the bushings 28 and is rotatably mounted therein, 70 the stud 55 being provided with an extension portion 56A which enters a slot or groove in a head portion of the shaft 57 which is rotatably supported at its inner end in the bushing 58 which is supported in the flange 59 of the bracket 60 75

5 by riveting as at 61 or by similar means, the shaft 57 being further rotatably supported at its outer end by the extension portion 62 engaging a bushing 63 suitably secured in the flange 64 of the bracket 60 by riveting at 65 or by similar means.

10 The extension portion 56A of the stud 55 enters the groove or slot 66 of the shaft 57 as above stated and the extension portion 56A and the head portion of the shaft 57, through which extends the slot 66, both extend within the bushing 67 which thus tends to support the end of the roller 26 on the shaft 57 and at the same time provides a driving connection between the roller 26 15 and the shaft 57.

15 It is now to be noted that the spring or resilient member 68 as disclosed in Figs. 3 and 4 is provided with an opening which extends around the extension portion 56A of the stud 55 and the head portion 56 of the shaft 57 through which extends the slot 66 to secure the spring 68 between the bushing 67 and the stud 55. The spring 68 is thus fixedly secured to the stud 55 and the shaft 57 so as to provide a driving connection 20 therebetween so that when the shaft 57 is driven as hereinafter described the extension portions 69 of the spring 68 will frictionally engage the outer surface of the flange 29 of the bushing 28 with which it forms contacts by the curved ends 70 of the spring 68, thus forming a frictional and relatively slidably driving engagement for the roller 26.

25 It is now to be noted that the electric motor assembly A, which is of the synchronized type and may be operated on any kind of electric current, is provided with the flanges 71 which are utilized for securing the electric motor assembly A to the land 2 of the base member 1 at a point between the rollers 23 and 26, the flanges 71 being secured by the screws 72 which extend through the flanges 30 71 to engage the base member 1.

35 The electric motor assembly A is provided with reduction gear mechanism suitably mounted in the extension housing 73 in a manner to provide a lower driving speed for the shaft 14 which is suitably mounted in the extension housing 73 and connected with the driving reduction mechanism therein but which is not disclosed and which may be of conventional design.

40 The driving shaft 14 of the electric motor assembly A thus extends at right angles to the longitudinal axis of the electric motor assembly A and is adapted to drive the hub member 75 which is secured to the shaft 14 by the pin 76 or by similar means to form a driving connection therebetween, the hub 75 being provided with a flange 77 which, together with the flange 78 threadably engaging the extension 79 of the hub 75, forms a clamping means for holding and driving the friction drive member 80 which is constructed of felt, rubber or similar material to provide a frictional driving engagement with the surface 81 of the frictional driven flange or disc 82 which is supported on the shaft 83 and is suitably connected therewith by the pin 84 or by similar means to form a driving connection therebetween, it being understood that the above mentioned frictional driving means may be replaced with fiber gear members or other mechanical driving mechanisms as desired.

45 The shaft 83 extends within the bore 85 of the head portion 86 of the shaft 87 and is connected therewith by the pin 88 or by similar means to form a driving connection between the shafts 83 and 87, the head portion 86 of the shaft 87 being 50 rotatably mounted in the bushing 89 which is

fixedly mounted in the flange 90 of the bracket 91A by riveting at 92 or by similar means.

5 The bracket 91A is further provided with the flange 93 to which is riveted the extension portion 94 of the shaft 95 as at 96. The bracket 91A is secured to the base member 1 by the screws 97. The shaft 87 and the shaft 95 extend within the sleeve or bushing 98 upon which is fixedly mounted the frictional driving member 91 which is similar to that disclosed at 80 but of a smaller diameter, the frictional driving member 91 being clamped by the flange portion 92 of the sleeve 98 and the nut 93A which threadably engages the sleeve 98.

10 The key 100 forms a driving connection between the frictional driving member 91 and the sleeve 98 and in a similar way a key 101 forms a driving connection between a frictional driving member 80 and the shaft 74.

15 It is to be noted that the shaft 87 is provided with a key way 102 which engages a key member 103 on the sleeve member 98 to form a driving connection between the sleeve 98 and the shaft 87, the sleeve 98, however, being further freely rotatable on the stud 95 which is fixedly supported in the flange 93 of the bracket 91A. The sleeve 98 is provided with a pair of flanges 104 having a groove 105 extending substantially therearound and therebetween, the groove 105 being slidably engaged by the extension portions 30 106 of the arm 107 which is suitably secured to the hub or nut member 108 which is provided with a thread having a relatively coarse or sharp pitch as indicated by the thread 109 formed in the control shaft 110 which is rotatably supported by its extension portion 111 having a bearing in the bushing 112 which is fixedly secured in the flange 90 of the bracket 91A by riveting as at 113 or by similar means, the shaft 110 being further supported by its extension portion 114 40 extending through and having a bearing in the bushing 115 which is fixedly secured to the flange 93 by riveting at 116 or by similar means.

45 The knob or handle 117 is supported on and secured to the extension portion 114 of the shaft 110 by the pin 118, the control shaft 110 thus being adapted to be rotatably supported by the knob or handle 117 and to actuate the hub or nut member 108 longitudinally of the shaft 110 to enable its arm 107 to slidably move the sleeve 50 98 longitudinally of the shafts 87 and 95 to position the frictional driving member 91 in various driving positions relative to the friction driven flange or disc 119, the full lines in Fig. 3 indicating the frictional driving member 91 as being substantially in a high speed position and in which position it is located relatively near the axis of the shaft 120 which supports the frictional driven flange or disc 119 which is secured to the shaft 120 by the pin 121, or by similar means.

55 The dotted lines 122 indicate the position of the frictional driving member 91 after it has been moved substantially to its low speed driving position relative to the frictional driven flange or disc 119 and the dotted lines 123 indicate the relatively low speed position of the hub or nut member 108 when the frictional driving member 122 is in its low speed driving position adjacent the peripheral portion of the frictional 60 driven flange or disc 119 as indicated by the dotted lines 122.

65 The shaft 120 is suitably and rotatably supported in the bushing 124 which is fixedly secured in the flange 125 by riveting at 126 or by 70 75

similar means. The shaft 120 is further rotatably supported in the bushing 127 which is fixedly supported in the flange 128 by riveting at 129 or by similar means.

5 It is to be noted that the flanges 125 and 128 are formed on the bracket 131 which is secured to the bracket 131 by the screws 132.

The pinion 133 is supported on the shaft 120 and is driven by means of the key 134, the pinion 133 driving the gear 135 which is rotatably secured on the shaft 136 which is fixedly secured in the bushing 137 by the pin 138, the bushing 137 being secured by riveting at 139, or by similar means, to the flange 125.

15 The gear 135 rotates between the bushing 137 and the nut 149 which is threadably mounted on the shaft 136, the nut 148 being provided with a pawl or driving pin 141 which is adapted to engage the Geneva gear or wheel 142 which is suitably secured to and fixedly mounted on the shaft 143 which is rotatably mounted in the bushing 144 which is fixedly secured in the flange 145 of the bracket 146 by riveting at 147 or by similar means.

25 The bushing 144 is provided with the extension portion 148 which extends through the flange 149 of the bracket 146, the bracket 146 being suitably secured to the bracket 131 by the screws 150.

The bushing 144 is provided with the boss 151 which supports the other end of the shaft 136.

30 The bevel pinion gear 152 is secured to the shaft 143 by the pin 153 or by similar means, the bevel pinion gear 152 meshing with and driving the bevel gear 154 which is mounted on the shaft 57 and secured thereto as by the pin 155.

35 The bevel gear 154 drives the shaft 57 which in turn drives the spring 68 as hereinbefore mentioned. The spring 159 is interposed between the washer 157 abutting the end of the bushing 124 and between the hub of the friction driven flange or disc 119 to eliminate chattering in the driving operation of the shaft 120 and its supported parts.

40 It is to be noted that the Geneva gear or wheel 142 together with its pin engaging member 141 is more clearly disclosed in Fig. 7 and provides the pin type of intermittent gearing for indexing or locating the shaft 143, together with the spring 68 and its operatively connected parts to a fractional part of a revolution, which thus drives the roller 26 by an intermittent revolving motion.

45 A roller may be mounted on the pin 141 if desired to eliminate friction in the engagement of the driving means with the Geneva gear or wheel 142.

50 It is to be noted that the intermittent driving operation of the Geneva gear or wheel 142, together with its driving mechanism will provide an intermittent operation of the roller 26 which will thus cause the portion 25 as well as the portion 17 of the scrolls, sheet or paper to pause and enable the operator to better read and stress the lines or words of a speech or address by permitting them to come up and disclose a certain number of lines at a given time through the lens 16, the movement of the scroll pausing for a pre-determined length of time as a given number of seconds and then automatically moving at a given speed to another predetermined or intermittent period, thus enabling the speaker to quickly and efficiently vision the words of his speech without the inconvenience of a continual movement of the scroll member.

55 The roller 24 is rotatably supported by ex-

5 tension portions 158 fixedly secured in the flanges 30 and provided with extension portions 159 which rotatably engage the flanges 160 of the brackets 161 which are located at opposite sides of the base member 1 and are secured thereto by the screws 162.

10 It is to be noted that the screw member 20 for securing the brackets 19 in position extend through the side walls of the cover or housing 3 and are adapted to be engaged by the nuts 163 which thus enable the operator to tightly or loosely engage the screws 20 to permit the lens 16, together with the brackets 19, to be moved upwardly or downwardly to adjust the lens 16 in the proper position in accordance with the desires of the operator.

15 The lens 16 is provided with a hairline 164 to facilitate the maintenance of the vision of the operator on the words or line of words which is being spoken, the movement of the roller intermittently bringing the lines of the words up to the hairline 164, the scroll pausing sufficiently with the line which is being read to be disclosed adjacent the hairline 164.

20 The light bulb 165 as disclosed in Fig. 2 may be suitably mounted and supported from the side wall of the brackets 19 so that it will illuminate the scroll 17 and the lens 16 to render the reading matter 166, as indicated in Fig. 6, visible through the lens 16 to the speaker, the light bulb 165 being automatically moved with the brackets 19 during their adjustment movement.

25 The electric switch 167 is suitably mounted in the housing or cover 3 at its forward position adjacent the clock mechanism 12 and is provided with a lever or button 168 readily operated by the speaker when standing adjacent the portable desk.

30 The side wall portions of the cover housing 3 are provided with slots 170 and 171 as disclosed in Fig. 2 to permit the cover housing 3 to operate by and adjacent the knobs or handles 51 and 111 at one side of the cover housing 3. The cover housing 3 may be provided with a suitable opening 172 through which extends the electric cable 173 which is electrically connected with the electric motor assembly A as disclosed in Fig. 3 to permit the cable 174 to extend outside of the cover housing 3 and to connect with a source of electric supply as with a conventional plug, thus permitting the electric plug to be plugged in to an electric source of supply such as is used in lighting buildings and similar structures.

35 The cables 173 and 174 are electrically connected to the switch mechanism 167 to permit control by the button or lever 168 after the cable 173 has been plugged in to its source of electric current.

40 The cable 175 is electrically connected at 176 to the clock mechanism 12 and may be connected with the cable 174 in the terminal point 176 to permit the clock mechanism to be automatically thrown into operation at the same time the electric motor assembly A is started in its operation, this being controlled by the operation of the button or lever 168 of the switch mechanism 167.

45 In a similar way a conventional electric connection may be made between the light bulb 165 and the switch mechanism 167 to enable the light bulb 165 to be illuminated at the same time the operation of the clock mechanism 12 and the electric motor assembly A is started.

50 In operation, the speech, music or words which the speaker, user or operator is going to use in

an address or in any way are printed on the scroll, sheet or paper 17 and then the scroll 17 is suitably secured to the roller member 23 and stretched over and in engagement with the roller 24 to disclose the portion 17 of the scroll, sheet or paper below the lens 16, the scroll being further extended by the portion 25 and suitably secured to the roller 26. Then with the beginning of the speech or music or words to be used in the 10 address or entertainment being initially positioned under the lens 16, the speaker or operator electrically connects the electric motor assembly A with a source of electric current which enables the electric motor assembly to be automatically 15 started by the operation of the button or lever 168 of the switch mechanism 167, the operation of the button or switch member 168 also plugging in and operating the clock mechanism 12 as well as illuminating the light bulb 165.

20 As the operator throws the button or lever 168 of the switch mechanism 167, the electric motor assembly A will begin to operate and rotate the shaft 74 which in turn drives the frictionally driven member 80 which by frictional engagement with the surface 81 of the frictional driven disc 82 will drive the shafts 83 and 87 which will in turn drive the frictional driving member 91 which in turn will drive the frictional driven flange or disc 119.

30 The driving of the frictional driven flange or disc 119 will drive the shaft 120 and the gear 133, the gear 133 in turn driving the gear 135 which drives the nut 140 together with the pawl or driving pin 141 which engages the Geneva 35 gear or wheel 142 with an intermittent motion to drive the shaft 143 which in turn drives the driving bevel gear 152 which drives the bevel gear 154 together with the shaft 57, which drives in turn the spring 68 which, with its frictional contact through the curved portions 70 with the outside surface of the flange 29, will drive the roller 26, the stud 55 rotating in the bore 56 of the flange 29.

40 The operator selects the speed at which the roller 26 operates by means of the nut member 103 which is movably operated longitudinally on the shaft 110 by the knob or handle member 117 to position the frictional driving member 91 as desired relative to the periphery of the frictional driven disc 119 to select a speed at which it is desired to have the scroll operate.

As the roller 26 is operated it will draw the portion 25 of the scroll 17 over the roller 24 and off of the roller 23 until the end of the words or 55 printed matter on the scroll 17 is past the hairline 164 of the lens 16.

It is to be noted and understood that due to the engagement of the pin 141 of the nut member 103 with the Geneva wheel or gear 142, each line 60 of words of the scroll 17 will be moved adjacent the hairline 164 and then the scroll 17 will pause a predetermined length of time and then again move automatically at a given speed so that the other lines of words are presented in their turn 65 adjacent the hairline 164.

The operation of the nut member 117 will thus retard or increase the speed of the scroll operating mechanism as desired by the operator and in accordance with the speed with which it is desired that the words on the scroll 17 are to approach the line 164.

Also it is to be noted that my scroll operating mechanism may be driven by the electric motor assembly A or it may be driven by hand by means 75 of the knob or hand members 51 which will thus

permit the operation of the rollers 23 and 24 due to the relatively slidable engagement of the spring 68 with the flange 29 of the roller 26.

It is to be noted that as the operator controls the operative movement of the scroll 17 past and, 5 under the lens 16, the clock mechanism 12 will inform him as to the passage of time as indicated by the conventional symbols, one of which is disclosed at 177 in Figs. 1 and 6.

When it is desired to insert or replace a scroll 10 17 on the rollers, the cover housing 3 is unlocked and may be swung upwardly on the hinge mechanisms 4 to permit ready accessibility to the operating mechanism normally maintained within the cover housing 3. 15

It is to be understood that the propelling or driving means of my invention may be altered or redesigned to meet various conditions and necessities without departing from the spirit and scope of my invention. 20

I claim:

1. In a portable desk for use by a speaker making an address, the combination of a base member, a cover housing pivotally mounted on said base member, a lens member mounted in an opening in said cover housing, a roller member rotatably supported by said base member in said cover housing, means for manually rotating said roller member, a second roller member rotatably supported by said base member in said cover housing, a second means for manually rotating said second roller member, a third roller member rotatably supported by said base member in said cover housing, a sheet or scroll suitably secured to and rolled on said first mentioned roller member and extending across said lens member, said sheet or scroll member engaging said third roller member and being suitably secured to said second roller member, said sheet or scroll being provided with the words of said address thereon, a shaft rotatably supported by said base in said cover housing, a friction drive member rotatably supported by said base member, a gear train driven by said friction drive member and provided with means for engaging and driving a Geneva wheel, a Geneva wheel rotatably supported by said base member and driven by said means of said friction drive member, a relatively 30 slidable mechanism driving said second roller member, said relatively slidable mechanism being driven by said Geneva wheel, a threaded 35 shaft rotatably mounted, manual means for rotating said threaded shaft, a nut member movably mounted on and adapted to be moved longitudinally of said threaded shaft by said threaded 40 shaft, said nut member being adapted to actuate said friction drive member to different driving positions, an electric motor assembly supported 45 in said cover housing, and drive mechanism operatively connecting said electric motor assembly and said first mentioned shaft. 50

2. In a portable desk, the combination of a scroll, roller means for moving said scroll, means for driving said first mentioned means, a housing covering said scroll and said roller means, 65 said housing being provided with an opening above said scroll, a pair of brackets oppositely disposed in said opening and each provided with portions for supporting a lens, and a lens supported in said portions of said brackets and extending within said opening of said housing. 70

3. In a portable desk, the combination of a scroll, roller means supporting said scroll, a shaft fixedly supported, a second shaft rotatably supported in alignment with said first mentioned 75

shaft, a sleeve member slidably mounted on said first mentioned and said second shafts and driven by said second shaft to rotate therewith, a third shaft rotatably mounted adjacent said first mentioned and said second shafts, a nut member movably mounted on said third shaft and adapted to be driven thereby axially thereof, said nut member being operatively connected with and adapted to shift said sleeve member axially of 10 said first mentioned and said second shafts, a friction drive member mounted on said sleeve member and driven thereby, a friction disc member driven by said friction drive member, means for driving said first mentioned shaft, means for 15 manually rotating said third shaft, power transmission means connecting said friction disc member and said roller means, and a lens supported above said scroll.

4. A portable desk of the type described, comprising a base, a housing disposed over said base and having side walls and a top wall, the top wall comprising a portion disposed at an angle to the horizontal, said portion having an opening, a lens disposed in said opening, bracket means 25 carried by the side walls for supporting said lens, devices carried by said base and disposed within said housing for supporting and moving a scroll past said lens in a plane parallel to the plane of said portion of said top wall, and means for adjustably moving said bracket means and said lens to and from said scroll.

5. A portable desk of the type described comprising a base, a pay-out roller and a take-up roller carried by said base, an idler roller carried 35 by said base and disposed substantially above the plane of the pay-out and take-up rollers, motor means carried by said base for rotating said take-up roller, means for intermittently transmitting power from said motor to said take-up roller, manual means for rotating said pay-out and take-up rollers, a housing supported by said base, and a lens carried by said housing and disposed over and in a plane parallel to the plane formed by said pay-out and idler rollers.

45 6. A portable desk of the type described comprising a base, a pay-out roller and a take-up roller carried by said base, an idler roller carried by said base and disposed substantially above the plane of the pay-out and take-up rollers, motor means carried by said base for rotating said take-up roller, means for intermittently transmitting power from said motor to said take-up roller, a housing supported by said base and a lens carried by said housing and disposed over 50 and in a plane parallel to the plane formed by said pay-out and idler rollers.

7. A portable desk of the type described comprising a base, a pay-out roller and a take-up

roller carried by said base, an idler roller carried by said base and disposed substantially above the plane of the pay-out and take-up rollers, motor means carried by said base for rotating said take-up roller, a housing supported by said base, 5 a lens carried by said housing, said lens being disposed in a plane parallel to the plane formed by said pay-out and idler rollers, and means for moving said lens to and from said last mentioned plane.

8. A portable desk of the type described, comprising a housing, the upper wall of said housing having two openings, an electrically operated clock disposed within said housing and in registry with one of said openings, devices disposed 15 within said housing for supporting and moving a scroll past the other opening, said devices comprising an electric motor and means for intermittently transmitting power from the motor to the scroll, and a switch carried by the housing 20 and electrically connected to the clock and the motor and controlling the simultaneous operation of both.

9. In a portable desk, the combination of a 25 housing, a pair of rollers mounted therein for supporting a scroll manuscript, means carried by each roller and disposed exteriorly of the housing for the manual rotation thereof and for manually feeding said scroll in either direction, a motor disposed within the housing, and intermittent power transmitting means connecting said motor to one of said rollers, the means comprising a relatively slidable device, thereby permitting the manual control of the movement of said scroll in either direction without interrupting the operation of said motor.

10. A portable desk comprising a base plate, an electric motor mounted on said base plate, a pay-out roller and a take-up roller carried by 40 said base for supporting and moving a scroll manuscript, an electric motor carried by said base, intermittent power transmitting means operatively interposed between said motor and the take-up roller, and a housing having two openings, an electric clock carried by said housing and exposed to view through one of said openings, and a lens carried by said housing mounted in the other opening, an electric switch controlling the clock and motor, said housing being hingedly mounted on said base and enclosing said motor 45 and rollers, and said power transmitting means; said rollers each having a knob exteriorly of the housing, and said power transmitting means comprising a relatively slidable device, thereby permitting the manual control of the operation of said rollers without interrupting the operation of said motor.

DAVID BARRON O'KELLY.
